ATTORNEY

UNITED STATES PATENT OFFICE.

STEPHAN KLAUS, OF HAWTHORNE, NEW JERSEY.

TOY.

Application filed February 17, 1927. Serial No. 168,858.

The main object of this invention is the provision of a novel and attractive toy which because of its unusual character compared to that of the usual class of toys, will give 5 much pleasure and amusement to children.

Another object is the provision of a toy constituting a basket supported on a post and an ejector which is spring actuated to throw a ball into the basket.

10 Another object is the provision of such a toy through novel means and through novel arrangement of parts.

The above and other objects will become apparent in the description below, in which 15 like-named characters of reference refer to like-named parts on the drawing.

Referring briefly to the drawing, Figure 1 is a perspective view of the toy as it appears after the ball has been ejected.

20 Figure 2 is a side elevational view of the same, with parts omitted for simplicity and with the ejector in section to illustrate the actuating mechanism.

Referring in detail to the drawing, the 25 numeral 10 represents a base supported upon legs 11. A post 12 rises vertically from one end of the base, and a basket of the type used in the game of basketball, indicated at 13, is supported by the post.

30 At the other end of the base a pair of vertical supports or uprights 14 are mounted in spaced apart relation, and between these a flat ejecting board 15 is pivotally mounted by means of a pin 16 passing through the 35 board and the uprights.

The lower side of the ejector 15 is indented at 17 and is therein engaged by the bent over end 18 of a coiled spring 19 which lies under the pin 16 and is retained between 40 the ejector and the base 10. The lower extremity of the spring 19 is bent downward at 21 to engage an indentation 20 in the base 10. Thus the spring is securely held in position, so that it normally urges its upper or 45 outer end upward, the distance to which said end may be moved upward being limited by the point of contact between the base and the lower or inner end of the ejector.

A circular hole 22 is provided near the 50 upper end of the ejector, and a ball 23 is adapted to recline in this hole. A cord 24

of a length slightly greater than the height of the basket 13 above the ground, is secured in a staple 25 to the base 10 at the foot of the ejector 15, and the ball 23 is attached 55 to the other end of the cord. The relative positions of the basket 13 and the hole 22 is such that a line drawn through the center of the hole 22 parallel with the long sides of the ejector 15, would pass through a 60 horizontal projection of the center of the basket 13.

The toy is operated as follows. The ball 23 is placed on the ejector 15 in the hole 22. The upper extremity of the ejector is then 65 depressed until it meets the base 10, and it is then released. The spring 19 causes that end of the ejector to fly upward, causing the ball 23 to be ejected upward and in the direction of the post 12. When the ball 70 reaches a distance equal to the length of the cord 24, it will be checked in its upward flight, and, because of its motion toward the post 12, it will momentarily rotate about the staple 25 in the direction of the post 12, at 75 the same time falling slightly. As soon as the cord 24 strikes the basket 13, the cord will be checked at the point of contact with the basket, but the ball will continue and drop into the basket. The operation as de- 80 scribed may then be repeated. It is to be noted that with the various parts of the device all properly constructed and mounted, the ball will invariably drop into the basket.

Having thus described the invention, I do 85 not wish to limit the invention to any particular construction except as specified in the accompanying claim.

What is claimed is as follows:

A toy comprising a rectangular base, a vertical post square in cross section extending upwardly from said base near one end, a basket open at the top and bottom mounted on the upper end of said post, a pair of spaced-apart uprights on said base near the end opposite to the post, a straight platform mounted pivotally between said uprights, a coiled spring mounted beneath the pivotal axis of said platform, one of the ends of said coiled spring seating upon said base, the opposite end of said coiled spring seating 100 upon the under side of said platform, the 105

coiled spring normally urging one end of said platform to contact with said base and raising the opposite end, said platform having an opening in the raised end, a ball 5 larger than said opening in said platform, said ball being adapted to be seated in said opening and a string attached to said ball,

the opposite end of said string being anchored to said base adjacent the end of said platform which contacts with said base, and the anchored end of said string being located at an acute angled position from said basket. 10

In testimony whereof I affix my signature.

STEPHAN KLAUS.
